UNITED STATES PATENT OFFICE.

OLA JOHNSON, OF CONWAY SPRINGS, KANSAS.

DOUBLE JACK FOR TELEGRAPH-CIRCUITS.

No. 806,812.

Specification of Letters Patent.

Patented Dec. 12, 1905.

Application filed March 16, 1905. Serial No. 250,402.

To all whom it may concern:

Be it known that I, OLA JOHNSON, a citizen of the United States, and a resident of Conway Springs, in the county of Sumner and State of Kansas, have invented a new and Improved Double Jack for Telegraph-Circuits, of which the following is a full, clear, and exact description.

My invention relates to telegraphy and kindred arts, my more particular object being to provide for shifting a plurality of circuits or parts of circuits, so as to throw one set of instruments out of commission and another set into commission. To this end I have so arranged the instruments and wiring that a telegraph operator is enabled by merely inserting a plug in a jack to shift parts of both the main and local circuits from the sending and receiving instruments located upon one table to other sending and receiving instruments located upon another table, all of the sending and receiving instruments being connected with a common relay.

My system is of peculiar value in cases where a telegraph operator normally uses a particular key and sounder, but may occasionally desire to use another key and sounder located in a different part of the room or upon a different table. For instance, an operator may use a particular key and sounder for ordinary railway-telegrams, but may desire to occasionally use another key and sounder for purposes of handling press-despatches, in which event the sounder last mentioned may be mounted within a resonator.

Reference is to be had to the accompanying drawings, forming a part of this specification, in which similar characters of reference indicate corresponding parts in all the figures. Fig. 1 is a diagram of the wiring and electrical connections for all of the instruments. Fig. 2 is a side elevation of the double jack, the plug of which is indicated as removed. Fig. 3 is a side elevation of the jack, showing the plug in position. Fig. 4 is a plan view of the jack with the plug removed, and Fig. 5 is an inverted plan view showing the bottom side of the plug.

The base of the jack is shown at 6 and is secured in position by means of screws 7, which pass through ears 8 for the purpose. Mounted upon the base 6 are contact-springs 9 10, adapted to engage stationary contact members

11 12. Under the spring 10 and out of contact therewith is an auxiliary contact member 55 13. The contact members 11, 12, and 13 are connected, respectively, with binding-posts 14, 15, and 16 by means of wires 17, 18, and 19, as indicated by dotted lines in Fig. 4 and in the diagram shown in Fig. 1. The contact-springs 9 10 are similarly connected with binding-posts 20 21 by means of wires 22 23. The jack-plug 24 is provided with a handle 25, whereby it may be manipulated at will. Upon the upper side of the plug are contact members 26 27, connected with respective binding-posts 28 29. Upon the under side of the plug and immediately below the contact members 26 27 are other contact members 31 30, as will be understood from Figs. 3 and 4. The contact members 31 30 are connected, respectively, with binding-posts 32 33 by means of screws 32^a 33^a, as will be understood from Figs. 3, 4, and 5. A "blind" binding-post 34 is mounted upon the plug 24 at a point adjacent to the handle 25. Line-wires are shown at 35 36 and enter the office through insulating-tubes 37 38 in the usual manner. Connected with the wire 35 and forming virtually a continuation thereof is a wire 39, which 80 leads to a key 40 and is provided with a circuit-closer 41. From this key a wire 42 leads to the binding-post 20 upon the jack. A wire 43 is connected with the binding-post 14 of the jack and is also connected with the relay 85 44, so as to energize the same by sending a so-called "main" circuit therethrough. A wire 45 is in communication with the line 36 for the purpose of completing the main circuit through the relay. The relay 44 is provided with a contact member 46, which is engaged by a contact-armature 47 in the manner well understood in the art. From the contact member 46 a wire 48 leads to a sounder 49, and from this sounder a wire 50 leads to the 95 binding-post 15 of the jack. An auxiliary wire 51 is connected directly with the wire 48 and leads from it to the binding-post 16 of the jack.

All of the apparatus thus far described may 100 be considered as mounted upon one table or in one corner of the room. In another corner of the room or upon another table are a plurality of keys 52 53, provided with circuit-closers 54 55 of the usual construction. The key 52 is connected by wires 56 57 with the

respective binding-posts 28 and 34. The key 53 is similarly connected by wires 58 and 59 with the respective binding-posts 34 and 32, as will be understood from the diagram. 5 Wires 60 61 respectively connect the binding-posts 33 and 29 with the sounder 62, which is preferably mounted within a resonator 63, the latter having a support 64 for maintaining the sounder in a comparatively elevated 10 position.

My invention is used as follows: If the operator desires to use merely the key 40, sounder 49, and relay 44, he withdraws the jack-plug, whereupon the contact-springs 9 10 of the 15 jack descend and by their resilience engage the contact members 11 12. The circuits may now be traced as follows: main line 35, wire 39, key 40, circuit-closer 41, (the key being normally closed for the purpose of receiving,) 20 wire 42, binding-post 20, wire 22, spring-contact 9, stationary contact 11, wire 17, binding-post 14, wire 43, relay 44, wire 45, and line-wire 36. This energizes the relay 44 and actuates the contact-armature 47, causing the 25 same to engage the contact member 46. The circuit used in sending by means of the key 40 is identical with that above described, except that the circuit-closer 41 being open the current goes through the body of the key 40 30 instead of through the circuit-closer, as is usual. The local circuit closed by movements of the contact-armature 47 is as follows: local battery 65, wire 67, contact-armature 47, contact member 46, wire 48, sounder 49, wire 35 50, binding-post 15, wire 18, stationary contact 12, spring-contact 10, wire 23, binding-post 21, and wire 66 back to the battery 65. This circuit of course energizes the sounder 49 in the ordinary way. Both circuits just 40 described are commonly used in the majority of telegraph offices in this country. Suppose now that the operator desires to shift the circuits to the other tables or to the other part of the room, as above suggested. He 45 may desire to do this, for instance, if he uses a type-writer and has difficulty in listening to the clicking of the sounder, and upon that account prefers to bring into requisition the resonator 63. He then inserts the jack-plug 50 as above described, the main circuit being now traced as follows: line-wire 35, wire 39, circuit-closer 41, wire 42, binding-post 20 of jack, wire 22, spring-contact 9, contact 26 of plug, binding-post 28, wire 56, key 52, (or circuit-closer 54,) wire 57, binding-post 34, wire 58, key 53, (or circuit-closer 55,) wire 59, binding-post 32, contact member 31 of plug, stationary contact 11 of jack, wire 17, binding-post 14, wire 43, relay 44, and wire 60 45 to line-wire 36. This energizes the relay 44, thereby completing the following local circuit: battery 65, wire 67, contact-armature 47, contact 46, wire 48, wire 51, (sounder 49 be-

ing now cut out,) contact-screw 16, wire 19, auxiliary contact 18, contact member 30 of 65 plug, binding-post 33, wire 60, resonator-sounder 62, wire 61, binding-post 29, contact member 27 of plug, spring-contact member 10, and wire 66 back to battery 65. It will thus be seen that both keys 52 and 53 are in 70 the main circuit, which coacts with the resonator-sounder 62, and that these keys can only be used when the plug is inserted. It will also be noted that the resonator-sounder 62 coacts with either or both of the keys and 75 that when the resonator-sounder is in use the sounder 49 is cut out. It is obvious that the resonator-sounder 62 is out of commission when the plug is withdrawn from the jack, for the reason that there is a total severance of 80 two circuits, of which the local circuit leading to the resonator-sounder is one. It necessarily follows that when either of the sounders is in use the other is totally silenced.

Having thus described my invention, I 85 claim as new and desire to secure by Letters Patent—

1. The combination of a relay, a main-line circuit for energizing the same, a local circuit connected with said relay and controllable thereby, a sounder connected with said local circuit and normally adapted to be energized thereby, an auxiliary wire connected with said local circuit for cutting out said sounder, a jack connected with said local circuit and also connected with said auxiliary wire, and a second sounder connected with said jack and adapted to be cut into circuit by aid of said wire for cutting out said first-mentioned sounder. 95 100

2. The combination of a relay, a main circuit connected therewith for energizing the same, a plurality of local circuits connected by means of said relay, a double jack connected with both said main circuit and said local circuits, a key and a sounder connected with said jack, and main wiring constituting virtually a continuation of the main line, said local wiring containing an extra sounder to be actuated in lieu of said first-mentioned sounder. 105 110

3. The combination of a relay, a main circuit connected therewith for energizing the same, a local circuit connected with said relay, a double jack connected with both said main circuit and said local circuit, a key and a sounder connected with said jack, and main and local wiring connected with said jack, said local wiring containing an extra sounder to be energized in lieu of said first-mentioned sounder. 115 120

4. The combination of a main circuit, a relay connected therewith and energized thereby, a local circuit connected with said relay, an auxiliary wire connected with said local 125 circuit and adapted to cut out said sounder,

another sounder adapted to be cut into said local circuit by aid of said auxiliary wire, and a jack connected with said last-mentioned sounder for cutting the same into circuit and 5 cutting said first-mentioned sounder out of circuit at will.

In testimony whereof I have signed my name

to this specification in the presence of two subscribing witnesses.

OLA JOHNSON.
